GEORGE B. OWEN, OF WINSTED, CONNECTICUT.

Design No. 3,224, dated November 3, 1868.

DESIGN FOR A CLOCK-CASE.

The Schedule referred to in these Letters Patent and making part of the same.

To all whom it may concern:

Be it known that I, GEORGE B. OWEN, of Winsted, in the county of Litchfield, and State of Connecticut, have invented a new and original Design for Clock-Case; and I do hereby declare that the following is a full, clear, and exact description thereof, which will enable others skilled in the art to make and use the same, reference being had to the accompanying drawings, forming part of this specification, in which—

Figure 1 is a front or face view of a wooden clock-case, constructed according to my design.

Figure 2 is a horizontal section of the same, taken in the line *x x*, fig. 1.

Similar letters of reference indicate like parts.

This invention relates to a new and improved design for a wooden clock-case, and of that class which are provided with a double-inclined or Gothic top.

In the accompanying sheet of drawings, A represents the base of the clock-case, which is of rectangular form, and has its upper edge rounded in semicircular form, as shown at *a*.

The front edges of the sides, B B, of the case are rounded, forming convex surfaces, *b b*, and the upper

ends of B have turned ornaments, C C, secured on them, as shown clearly in fig. 1.

The top of the clock has a double-inclined or Gothic top, the front edges of the sides, D D, of which have a rounded or convex surface, *c*, to correspond with the convex surfaces, *b b*, of the sides B.

To the inner edges of the convex surfaces *b b*, *c c*, and also to the top of the base, A, there is attached a moulding, E, of gilt, which extends all around; and within this moulding the door F is fitted, the whole forming a chaste and ornamental design for a wooden clock.

Having thus described my invention,

I claim as new, and desire to secure by Letters Patent—

The design for a clock-case, as herein shown and described.

The above specification of my invention signed by me, this 3d day of August, 1868.

GEO. B. OWEN.
